CLAIM

The ornamental design for an LED lamp, as shown and described.

DESCRIPTION

FIG. 1 is a front view of an LED lamp;

FIG. 2 is a rear view thereof;

FIG. 3 is a left-side view thereof;

FIG. 4 is a right-side view thereof;

FIG. 5 is a top view thereof;

FIG. 6 is a bottom view thereof;

FIG. 7 is a front perspective view thereof; and,

FIG. 8 is a rear perspective view thereof.

The broken lines shown in the drawings are for the purpose of illustrating portions of the LED lamp that form no part of the claimed design.
